FLOAT COLLAR AND CEMENTING SHOE

Robert N. Burnett, deceased, late of Monrovia, Calif., by Sylvester Hoffmann, executor, Glendale, Calif.

Application July 12, 1941, Serial No. 402,163

5 Claims. (Cl. 166—1)

This invention relates to a float collar and cementing shoe, particularly useful in cementing of casing and pipe in an oil well.

The modern art of cementing strings of casing is one of the well known procedures in oil field practice. The general purpose of such procedure is the exclusion of water from productive formations. Oil well cementing requires the placing of cement slurry at the proper place in the well, to cement a string of casing and to seal off the passage of fluid or gas past the point which it is desired to plug.

In running casing for this purpose, especially in wells which attain great depths, a tremendous strain is placed upon equipment due to the enormous weight of the casing.

It is one of the objects of this invention to provide a means for sealing off the end of the casing so as to permit the casing to be buoyed up by the fluid which is in the well.

This is accomplished by means of a valved closure which will remain closed during the running of the casing so as to exclude the formation fluid from the interior of the casing or tubing which is being run and so permit the buoyant action of the fluid to relieve the strain on the lowering and suspending equipment.

In order that this float collar may also be usable as a cementing shoe, provision is made in the float collar of this invention for the opening of the valve on the imposition of hydraulic pressure to permit the discharge of the cement therethrough. By means of this hydraulically operated valve structure a quick closing operation is made possible which seals the closure upon the release of hydraulic pressure, thus preventing the backward migration of cement into the tubing or casing.

It is an object of the invention to devise a float collar and casing shoe which may be employed in any of the methods of cementing.

In employing the float collar in any of these methods, a number of advantages are attained. The float collar may be placed either at the end of the tubing when the tubing method is used, or at the end of the casing when the casing method is used. It will permit the floating in of the casing or tubing to relieve the strain on the equipment. The cement may then be introduced into the tubing or casing and while it is so introduced it is kept away from contamination by the fluid in the well. As is well known, the strength of the cement is deleteriously affected on mixture with this mud fluid. When the proper amount of cement has been introduced into the

tubing or casing which is sealed by the float collar and cementing shoe of this invention, water may be introduced to create water pressure on top of the cement. The pump pressure, when raised to the required amount, will open the ports of the cement shoe and permit a discharge of the cement through the ports.

The ports are placed on the side wall of the shoe, which are preferably at a distance above the end of the bore hole. This prevents these ports from becoming clogged by the settled mud or collected detritus which is usually found at the bottom of the bore hole even though a washing operation has been employed to prepare the hole for cementing.

This float collar and cementing shoe is also useful in the so-called full hole method of cementing combination strings of casing. A combination string of casing is composed of blank casing, that is, imperforate casing, and perforate screen liner. In cementing this type of combination string, difficulty has been found in washing over the whole length of the casing due to the fact that the perforate liner does not permit the stream to pass the full length of the liner. To avoid this difficulty, it is desirable to employ a liner of such construction that it is imperforate during the washing operations and may be either drilled out or made perforate when the cementing operation has been completed. Such a liner may be the form of liner disclosed in the copending application Serial No. 300,313, filed Oct. 20, 1939, and now abandoned. The walls of the liner contain soluble portions which, upon reaction with acid, are eaten out to provide the desired passages in the walls thereof.

In cementing such a combination string, the float collar and cementing shoe of this invention may be placed either at the end of the string or at a point between the imperforate casing and the perforate casing. The cementing procedure is then much the same as in the methods herein described. The cement discharges through the open ports of the cementing shoe under the influence of hydraulic pressure and is placed in position behind the casing wall.

This invention will be better understood by reference to the drawing, of which:

50 Fig. 1 is a fragmentary view of casing showing the position of the float collar and cementing shoe, it being shown in exterior front elevation.

Fig. 2 is a vertical section taken along line 2—2 of Fig. 1.

55 Fig. 3 is a schematic assembly view showing

the location of the cementing shoe and the cementing of the casing.

The cementing shoe is composed of an exterior barrel 1, provided with screw threads into which may be screwed the casing or tubing 14 used in the cementing operation. The barrel is provided with ports 5 shown as four in number in the drawing, and with ports 9, also shown as four in number. The interior of the lower end of the barrel is sealed by a disc 11 which is screwed into or otherwise attached to the barrel 1.

In the barrel 1 is provided a recess 2, into which is fitted a helical spring 3. Inside the barrel 1 is positioned a slideable sleeve 4 provided with a lip 6 which is resiliently supported upon said spring 3. The lower end of said sleeve 4 is provided with a series of cut out portions 7, whose function will be described later. On top of said lip 6 of the sleeve 4 is set a second sleeve 8 provided with ports 10, equal in number to the ports 5. The end of the sleeve 8 is closed by a disc 11', which is screwed in or otherwise attached to the sleeve. The sleeve 8 is retained in place by a retaining ring 12, which is screwed into position in the barrel 1.

The barrel assembly is screwed onto the end of the tubing or casing 14. In the event additional lengths of casing or tubing or screen are to be attached to the end of the barrel 1, it may be done as shown at 13.

On the lowering of the casing or tubing into the well, the hydrostatic pressure of the fluid outside the casing is transmitted through ports 9 against the bottom of the disc 11'. A hydrostatic pressure is created in the chamber between said discs and the sleeve 4 and sleeve 8 are moved upward against the retaining ring 12 so that the ports 10 are moved out of register with ports 5 and the interior of the tubing or casing is sealed as shown in Fig. 2.

When the cement has been introduced and deposited inside the tubing or casing above the upper disc 11', hydraulic pressure, generated for example by means of the pump 15, will move the sleeve 8 and the sleeve 4 downward against the spring 3 and overcome the hydrostatic pressure of the fluid, causing its discharge from the interior of the chamber between the discs 11 and 11' through the ports 9. Upon the downward motion of the sleeve 8, port 10 comes into register with the port 5, thus permitting the discharge of the cement through port 10 and port 5 into the exterior of the casing or tubing.

The cut out portion 7 of the sleeve 4 is provided for the purpose of keeping the ports 9 open. When this cement has been discharged through 10 and 5, the pump pressure is relieved and the hydrostatic pressure on the exterior of the casing, acting through open ports 9 and the spring will move the sleeve 4 and therefore the sleeve 8 upward until the sleeve 8 abuts against the retaining ring 12. This seals the ports 5 again, thus preventing the intrusion of cement from the exterior of the casing back into the interior of the casing. When the cementing operation is completed, the discs 11 and 11', which may be conveniently of cast iron, may be drilled through by means of a fish tail bit or any other cutter, as will be well understood by those skilled in the art.

As will be observed from the construction and operation of this combined float collar and casing shoe, the tubing or casing may be floated in because during the descent of the tubing or casing which is attached to the float shoe, the interior of the tubing or casing is sealed off from the ex-

terior by means of the discs 11 and 11' which form a closure upon the bore of the tubing 14. The interior of the casing or tubing above the disc 11' may be empty or may contain a desired amount of fluid and thus a controlled buoyancy of the string of tubing or casing is attained. This buoyancy will relieve the strain on the lowering equipment.

The casing shoe is operable with the open hole cementing method, since the valve structure is operated by hydraulic pressure and does not need the cooperation of an inserted plug for its functioning. However, it can be used with the plug method of cementing, the plug being so designed as to seal the ports 10.

The use of a combination float collar and cementing shoe also insures that the interior of the casing or tubing into which the cement is to be placed is not contaminated by the fluid which is in the well. As is well known, if mixed with cement, such fluid weakens the strength of the cement. The employment of a hydraulically operated cementing shoe permits of a rapid closure of the cement ports which insures that cement will not back up into the casing when the pressure is relieved at the pump.

The provision of side wall ports as formed in this invention permits of large openings through which the cement will pass without excessive agitation at the points of introduction into the annulus behind the casing. This is an advantage since it limits the mixing of the cement with the fluid in this annulus and thus insures a cement of high strength.

The use of closure discs permits of an easy re-opening of the passage by means of a simple cutter without introducing a constriction in the tubing or casing if the tubing or casing is, as a result of the cementing operation, to remain in the bore hole.

It is to be understood that the foregoing description of an embodiment of the invention is illustrative only and various changes and modifications may be made therein without departing from the spirit of the appended claims.

What is claimed is:

1. A combination float collar and cementing shoe which comprises a barrel, ports in said barrel, means for attaching said barrel to tubing or casing, a sleeve in said barrel, ports in said sleeve, resilient means to hold said sleeve so that the ports in said sleeve are out of register with the ports in said barrel and said sleeve ports are sealed against the wall of said barrel, and a permanent closure for the lower end of said sleeve to prevent flow of fluid through said bore from passing through said sleeve and passing said closure.

2. A combination float collar and cementing shoe which comprises a barrel, upper ports in said barrel, means for attaching said barrel to tubing or casing, a retaining ring in the upper portion of said barrel and secured to said barrel, a sleeve slidably mounted in said barrel below said retaining ring, ports in said sleeve, a closure positioned in said sleeve below the ports in said sleeve, said closure entirely closing off the lower end of said sleeve, a second sleeve slidably mounted in said barrel abutting said first mentioned sleeve below said closure, a resilient support for said second sleeve normally holding said first and second mentioned sleeves at their upward extremity of motion in said barrel against said retaining ring so that said first mentioned ports in said barrel and the ports in said first mentioned sleeve are out of register, continually open

ports in the barrel beneath said closure, and a second closure in said barrel beneath said second mentioned ports and entirely closing the bore of said barrel, whereby upon the imposition in the interior of said barrel above the closure in the first mentioned sleeve of hydraulic pressure in excess of the combined pressure exerted upwardly against the closure by said resilient support and the hydrostatic pressure in the barrel, said first mentioned sleeve moves downwardly to bring the ports therein into register with the first mentioned ports in the barrel, said resilient support being arranged, upon relief of said hydraulic pressure, to move the first and second mentioned sleeves upwardly until the first mentioned sleeve engages the retaining ring, thereby moving the ports in the first mentioned sleeve out of register with the first mentioned ports in the barrel.

3. A valve structure for oil well tubing comprising a barrel, a port in said barrel connecting the inside and outside of said tubing, a sleeve in said barrel slidably mounted in said barrel, a port in said sleeve, a diaphragm in said sleeve below said last-named port, and a second port in said barrel beneath said diaphragm connecting the interior of said barrel beneath said diaphragm with the exterior thereof during the sliding motion of said sleeve, whereby on imposition of hydraulic pressure in the interior of said barrel above said diaphragm said sleeve slides to bring the two first-named ports into register and on release of said pressure on the interior of said barrel, the hydraulic pressure on the exterior of said barrel moves said sleeve to close said two first-named ports.

4. An oil well cementing device adapted to be attached to a string of tubing or casing to be used in a cementing operation in a bore hole, which comprises a tubular member, a fixed closure for said tubular member to close the bore

- 10 of said member against flow of fluid through said tubing, means for attaching said member to said tubing or casing, a side wall port in said tubular member connecting the interior of said tubing with the exterior thereof above said closure, an hydraulically operated sleeve in said tubular member, a yieldable support for said sleeve, a port in said sleeve, hydraulically actuated means associated with said sleeve for moving it against the yieldable support upon the imposition of hydraulic pressure within said casing, a stop for said sleeve to limit its motion upon the imposition of the hydraulic pressure, said port in said sleeve being in register with the port in said 15 tubular member when said sleeve has reached said stop, said sleeve moving in the opposite direction upon the relief of said hydraulic pressure, whereby said ports move out of register upon said latter motion of said sleeve, and a stop for said latter motion.
- 20 5. An oil well cement device adapted to be attached to a string of tubing or casing to be used in a cementing operation in a bore hole, which comprises a tubular member, means for attaching said member to said tubing or casing, a port connecting the interior of said tubing with the exterior thereof, an hydraulically operated valve structure in said member, a closure for the bore of said member positioned in said valve structure for maintaining the bore of said tubular member closed, said valve structure being operable to open said port upon the imposition of hydraulic pressure in the interior of said member, while maintaining the bore of said member closed, 25 and to close said port upon the release of said hydraulic pressure while maintaining the bore of said member closed.
